By Richard Owen,

ATTORNEY

UNITED STATES PATENT OFFICE.

WILLIAM SHEPHERDSON, OF SANDPOINT, IDAHO.

WRENCH.

1,266,869.

Specification of Letters Patent. Patented May 21, 1918.

Application filed November 15, 1917. Serial No. 202,192.

To all whom it may concern:

Be it known that I, WILLIAM SHEPHERDSON, a citizen of the United States, residing at Sandpoint, in the county of Bonner and 5 State of Idaho, have invented certain new and useful Improvements in Wrenches, of which the following is a specification.

This invention relates to wrenches, and more particularly to that type of wrench 10 employing a fixed jaw and a slidable jaw movable toward and away from the fixed jaw.

One of the main objects of the invention is to provide a wrench of the character 15 stated of simple construction and operation. A further object is to provide a wrench composed of a minimum of parts and which may be produced at comparatively small cost. A further object is to provide a 20 wrench in which the movable jaw may be quickly and easily adjusted, the means for adjusting this jaw also serving to lock it in adjustment. Further objects will appear from the detailed description.

25 In the drawings:

Figure 1 is a side view of a wrench constructed in accordance with my invention as applied.

Fig. 2 is a perspective view of the movable 30 handle.

Fig. 3 is a perspective detail of the adjusting pawl.

Fig. 4 is a view similar to Fig. 1 of a wrench adapted for gripping pipes and 35 similar cylindrical objects.

Fig. 5 is a section taken substantially on line 5—5 of Fig. 1.

The wrench is provided with a metal handle or shank 1 of rectangular cross section 40 which is provided at one end with the integral gripping head 2. The intermediate portion of the inner or upper face of shank 1 is toothed to provide a rack 3, the teeth of this rack being directed toward jaw 2. 45 A keeper or sleeve 4 is slidably mounted on handle 1, the eye of this sleeve being of slightly greater width than handle 1 so as to permit limited rocking movement of gripping jaw 5, which is formed integral with 50 the sleeve, toward and away from the fixed jaw 2. Movable jaw 5 is provided in each lateral face and adjacent the upper outer corner thereof with a substantially U-shaped cut-out or recess 6. These recesses are 55 adapted to receive the spaced ears 7 which are formed integral with the movable handle

8 at the inner end thereof, these ears receiving snugly between them the bridge or web member 9 of jaw 5 formed by the recesses 6. Web member 9 and ears 7 are provided with 60 alined bores which receive a pivot pin 10 for pivotally securing the inner end of handle or lever 8 to jaw 5. Handle 8 is provided, in rear of pivot pin 10, and in each lateral face, with an outwardly directed recess 11. These recesses are adapted to receive the spaced arms 12 of a pawl 13 the point 14 of which is curved downwardly for engagement with the rack 3. The arms 12 of the pawl and the web member 15 of handle 8 intermediate the recesses 11 are provided with alined bores which receive a pivot pin 16 for pivotally securing the pawl to the arm. By raising the arm 8 and bringing the pawl 13 into engagement with any one 70 of the teeth of rack 3, selectively, as indicated by broken lines in Fig. 1, and then forcing handle 8 toward handle 1, the movable jaw 5 may be forced toward the fixed jaw 2 so as to tightly grip an object placed 75 between these two jaws. During this operation, the pawl 13 and the portion of arm 8 between the pivot pins 10 and 16 constitute a toggle lever for forcing the movable jaw toward the fixed one. 80

As will be noted, the ears 7 of handle 8 are offset or directed upward at an angle to the handle so as to bring the pivot pin 10 well above pivot pin 16 when handle 8 is in operative position as in Fig. 1. When an 90 object, such as the nut 17 is gripped between the jaws 2 and 5, the jaw 5 being forced tightly into engagement with this object, the line of pressure exerted on this jaw will be transmitted to the handle 8 through pivot 95 pin 10 so as to pass above pivot pin 16 and the axis of this handle. As a result of this, the pressure from jaw 5 tends to rock the outer portion of handle 8 downward about the pivot pin 16. This results in bringing 100 the shoulders 18 formed at the upper edges of the recesses 11 in handle 8 into engagement with the upper edges of the arms 12 of pawl 13 thus exerting downward pressure on the pawl so as to maintain it in engagement with rack 3. The pawl 13 and the portion of handle 8 intermediate the pivot pins 10 and 16 thus constitute, in addition to adjusting means, an eccentric lock for locking the jaw 5 in adjustment. For convenience in operating the adjusting means, handle 8 is provided adjacent its inner end with 105

a shoulder 19 which engages a coöperating shoulder 20 formed at the upper corner of movable head 5 so as to positively limit the upward movement of this handle. The operation of the wrench shown in Fig. 4 of the drawings is the same as that above described, the only difference being that the gripping jaws are shown as concave and toothed in the manner of a pipe wrench so as to grip cylindrical objects firmly when moved into engagement therewith.

As will be noted from Figs. 1 and 3 of the drawings, when the wrench is in gripping engagement with an object, the axis 5 of the pin 16 of the pawl 13 will be positioned on a straight line connecting the axis of pivot pin 10 to the free end of the pawl. This results in bringing the axis of the pawl on dead center with the fulcrum of the toggle lever and the axis of pin 10. In this manner, the movable jaw is positively locked in tight gripping engagement with the object. Also, by bringing the axis of pivot pin 16 on the line connecting the axis of pin 10 and the free end of the pawl, all loosening of the grip on the object, such as would occur if the toggle lever composed of the pawl and the inner end portion of the lever arm 8 were folded downwardly, is avoided. In addition, the locking of the jaw is easily effected, and the handle or lever 8 may be raised with but slight exertion.

Copies of this patent may be obtained for five cents each, by addressing the "Commissioner of Patents, Washington, D. C."

What I claim is:

In a wrench, a handle provided at one end 35 with a fixed gripping jaw, a movable gripping jaw slideable on said handle, the handle being provided in its inner face with an intermediate rack portion, a movable handle pivotally secured at its inner end to said 40 slideable jaw, and a pawl pivotally secured at its inner end to said movable handle intermediate the ends thereof and adapted to engage the teeth of the rack so as to force the movable jaw toward the fixed jaw when 45 the movable handle is depressed, said pawl and the movable handle being provided with coöperating shoulders acting to positively limit movement of the movable handle toward the handle of the fixed jaw so as to 50 bring the axes of the pawl and the movable handle into alinement with each other and with the free end of the pawl when said movable handle is moved into its extreme depressed position, the pawl and movable 55 handle thus coöperating with the movable jaw to form a lock for positively preventing movement of said movable jaw away from the fixed jaw.

In testimony whereof I affix my signature 60 in presence of two witnesses.

WILLIAM SHEPHERDSON.
